UNITED STATES PATENT OFFICE

2,633,940

BRAKE WEAR TAKE-UP

George W. Olson, Rochester, Minn.

Application March 8, 1948, Serial No. 13,589

3 Claims. (Cl. 188—79.5)

1

My invention relates to improvements in portable hoists or winches, for handling and lifting various kinds of objects and materials, and the primary object is to provide an all position, high speed, light duty device which is readily portable for movement to and about the job as required.

Another object is to provide a hoist of this character which is simple and light in construction and which has means for conveniently mounting it in any position on the floor, wall, or overhead, as may be required.

Another object is to provide a hoist having a rope or cable drum driven by a motor and with a novel, efficient and long wearing manually controlled brake mechanism for holding the drum in any position.

These and other more detailed and specific objects will be disclosed in the course of the following specification, reference being had to the accompanying drawings, in which—

Fig. 1 is a side view of my improved hoist showing the same hung from an overhead building timber.

Fig. 2 is a side view, taken from the opposite side, showing another position in which the hoist may be operated.

Fig. 3 is a plan view of the hoist in the position of Fig. 2.

Fig. 4 is an enlarged fragmentary side view with a part of the brake mechanism removed.

Fig. 5 is an enlarged sectional view through the brake mechanism and adjacent parts of the frame and drum, taken approximately along the line 5—5 in Fig. 4.

Fig. 6 is another fragmentary side view with other parts of the brake removed and shown in section.

Referring now more particularly and by reference characters to the drawing, my improved hoist as shown therein comprises a frame made up of two main side members or bars bent back in rounded formation at 10 providing parallel legs 11 which are joined at their ends by cross bars 12. A length of tubing 13 is welded across the rounded ends 10 of the frame to tie them together and also to form a carrying handle, as will be readily understood.

Bearing or end plates 14 and 15 are welded across between the legs 11 of the respective side members adjacent the rounded ends 10 thereof and these plates carry anti-friction bearings 16 on their inner sides, mounted by bearing cups 17 and bolts 18. See Fig. 5. A winch spool or drum 19 is provided and has a shaft 20 which is journaled at its ends in and between the bear-

2

ings 16. Screw plugs 21 are threaded through the plates 14 and 15 and may be removed for oiling the bearings 16. The spool 19 has a center barrel 22 and enlarged circular ends 23 and the location of the bearings 16 is such that this spool will fit nicely and rotatably in the rounded end of the frame as clearly shown in the drawing.

An electric motor 24 is mounted upon a mounting plate 25 (Fig. 2) welded between corresponding legs 11 of the respective frame side members and the power shaft of the motor has a small sprocket gear 26 in line with a large sprocket gear or ring 27 secured, as by rivets 28 seen in Fig. 5, to one end 23 of the spool. A sprocket chain 29 runs over the gears 26 and 27 so that the motor will rotate the spool and the spool will, of course, be provided with the usual cable or rope 30 so that this power rotation may be utilized to handle and hoist various loads connected to the cable.

The lower edges of the end plates 14 and 15 have outwardly turned stiffening flanges as shown at 31.

The frame also includes tie bars 32 (Figs. 1 and 2) and another mounting plate 33 joining the legs 11 opposite the motor and thereabove. Cross bars 34, above the bars 12, stiffen the intermediate part of the frame, and the mounting plates 32 and 25, while a guard plate 35 below the spool 19 protects the motor 24 from dirt and arcuately cut end shields 36 below the spool and at the sides thereof substantially close the spaces between the guard plate 35 and adjacent lower edges of the spool ends 23. This frame, as will be readily appreciated, is quite light in weight but due to the use of angle irons for most parts it is very strong and rigid and also inexpensive. In addition, the frame is neat and by its shape lends itself well to the mounting of the hoist 40 in any position about the job.

In connection with the latter feature, attention is called first to a pair of spaced, parallel mounting angles or bars 37 which are secured to the rectangular or lower end of the frame. These angles have openings 38 and are spaced apart to straddle a stock width and thickness of timber or lumber, indicated at 39 in Figs. 2 and 3. The hoist may be secured to the timber 39 by nails or screws (neither shown) through the openings 38 so that the timber acts as a base having a long footing on the floor. Then by piling bags of cement, or other heavy material found around the job, on the timber 39 the hoist will be firmly but temporarily held on the floor 50 while being used. Alternatively the hoist may

be mounted on a corresponding timber on the wall or ceiling as may be required. In addition, and particularly for some jobs, the hoist has a bracket 40 welded to the mounting plate 34 and having a hook 41 and stiffening webs 42. A bolt 43 passes through the bracket and engages a clamp plate 44. The bracket may be hooked over an overhead beam 45 (Fig. 1) and the clamp plate 44 pulled tight by the bolt 43 to solidly anchor the hoist in this position as will be readily understood.

To stop the rotation of the spool whenever required, and to hold the load, I provide a brake mechanism which will now be described. Referring particularly to Figs. 4-6, this mechanism is seen to include a brake drum 46 having a circular flange 47 and this drum is set into one end of the spool 19 through circular openings 48 in the spool end and the sprocket ring 27 and welded in place to rotate with the spool. Positioned inside the drum are two conventionally brake surfaced brake shoes 49 and 50 of arcuate shape and at two adjacent ends these shoes are oscillatably mounted by being screwed upon anchor screws 51 and 52 respectively. These screws 51 and 52 extend out loosely through openings 53 in the adjacent end plate 14 and secured on the screws are collars 54 and 55 having reduced neck portions 56 (Fig. 5) also loosely fitting said openings 53. Set screws 57 are used to secure the collars 54 and 55 upon the respective anchor screws 51 and 52. Outwardly of the end plate 14 the collars 54 and 55 are cam shaped (Fig. 4), having flats 58 on adjacent surfaces, and positioned between these flats, in contact therewith, is a screw 59 by which a channel shaped lock clip or clamp 60 is secured in place, with its edges bearing on the collars.

The opposite ends of the brake shoes 49 and 50 swing together or apart about the pivot connections with the anchor screws 51 and 52 and for adjusting the shoes in this manner, I provide an actuating cam 61 which is positioned between the shoe ends. A retractile coil spring 62 connects the shoes to normally pull them together and hold their ends in engagement with the cam 61. The cam is affixed to the inner end of a short shaft 63 journaled through a bearing 64 and provided, outside the end plate 14, with a hand lever 65. It will be readily understood that by moving the hand lever 65 the cam 61 may be rocked to spread the adjacent ends of the brake shoes 49 and 50 so that they will frictionally engage the brake drum and hold the spool 19 whereas opposite movement of the handle will allow the spring 62 to contract the shoes pulling them out of such braking engagement with the drum.

The bearing 64 is formed at the end of an adjusting slide 66 extending along the outer side of the end plate 14 and having one end 67 bent over and spaced from the adjacent edge of the frame leg 11. A cap screw 68 is placed through this end 67 and screwed into the leg 11 so that the slide 66 may be adjusted toward and away from the axis of the spool shaft 20. The bearing 64 passes inwardly through a slot 69 in the end plate 14 to permit such adjustments, while a lock screw 70 is passed through a slot 71 in the slide and screwed into the end plate 20 that the slide may be firmly secured in any adjusted position.

This adjustment of the slide 66 permits the cam 61 to be moved inwardly or outwardly, in a radial direction, between the ends of the brake

shoes 49 and 50. The cam 61 is tapered, being widest at its outer side as seen in Fig. 6, and such adjustment of the cam by the slide is utilized to take up wear on the shoes and drum. In other words, as wear occurs the cam 61 may be moved inwardly, by adjusting the screw 68 and then tightening the lock screw 70, to spread the shoes at this end and compensate for such wear.

It is to maintain even bearing or braking surfaces around the shoes as the wear occurs that I have provided the mounting previously described for the anchored ends of the shoes. Normally the anchor screws 51 and 52 and collars 54 and 55 are held tightly in position by the clip 60 but by loosening this clip the collars may be turned slightly and as they are so turned their flats 58 engaging the screw 59 will force the collars apart to correspondingly spread these ends of the brake shoes and compensatingly adjust them for wear as the cam 61 is moved inwardly for the same purpose. The clip may, of course, be retightened to hold each adjustment as made.

The useful life of the brake will obviously be greatly extended by these adjustments, and the simplicity with which they may be carried out even with only pliers for tools, is of great importance to my hoist since, by its very nature, it is in many cases subject to abuse and misuse by unskilled and careless workmen. It will be further noted in this connection that while the frame assembly is of welded construction throughout for simplicity and durability, all parts subject to wear are mounted by screws and the like so that they may be readily replaced when worn.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. For a hoist spool, a brake mechanism comprising a brake drum carried by the spool, a pair of arcuate brake shoes cooperating with the drum, cam means pivotally supporting two adjacent ends of the shoes so that their other ends may swing apart into engagement with the drum, said cam means being also operative to adjust the spaces between the pivoted ends of the shoes, a manually actuatable cam for spreading the other ends of the shoes, a slide supporting the cam for radial adjustment with respect to the axis of the spool, and the cam being tapered whereby such adjustment thereof will adjust the spread between the cam actuated ends of the shoe.

2. For a hoist having a frame and a spool, a brake mechanism of the character described, comprising a brake drum secured to the spool, a pair of arcuate brake shoes cooperating with the drum, anchor screws pivotally mounting two adjacent ends of the shoes on the frame, cams supporting said anchor screws, means for adjusting said cams to adjust these ends of the shoes with respect to the drum, an actuating cam positioned between the opposite ends of the shoes and said actuating cam being inwardly tapered toward the axis of the drum whereby oscillation of this cam will spread these ends of the shoes, means for moving the actuating cam, and means supporting the actuating cam on the frame for movements radially of the drum to adjust the adjacent ends of the shoes with respect to the drum.

3. For a hoist having a frame and a spool, a brake mechanism of the character described, comprising a brake drum secured to the spool, a pair of arcuate brake shoes cooperating with the drum, anchor screws pivotally mounting two adjacent ends of the shoes on the frame, cams supporting said anchor screws, means for adjusting said cams to adjust these ends of the shoes with respect to the drum, an actuating cam positioned between the opposite ends of the shoes and said actuating cam being inwardly tapered toward the axis of the drum whereby oscillation of this cam will spread these ends of the shoes, means for moving the actuating cam, means supporting the actuating cam on the frame for movements radially of the drum to adjust the adjacent ends of the shoes with respect to the drum, a clamp screw on the frame between the cams carrying the anchor screws and opera-

tively engaging said cams, and a clamp secured by the clamp screw over the cams.
